CLAIM

We claim the ornamental design for a non-slip headband, as shown and described.

DESCRIPTION

This application is related to U.S. patent application Ser. No. 13/087,735, filed on Apr. 15, 2011, entitled, "Non-slip hair accessory."

FIG. 1 is a top/rear isometric view of the headband of the present invention;

FIG. 2 is an opposing perspective view thereof;

FIG. 3 is a top plan view of the headband of FIG. 1; the bottom plan view is not shown as it mirrors the top plan view.

FIG. 4 is an alternative perspective view of the headband of FIG. 1, shown as it would appear when not worn, and laid on a flat surface.

FIG. 5 is an enlarged detail perspective view taken from one end of the non-slip strip as shown in FIG. 4; and,

FIG. 6 is an enlarged detail plan view taken from one end of the non-slip strip as shown in FIG. 4.

The broken lines in FIG. 6 show the bounds of the view, and form no part of the claimed design.
